ATTORNEY.

UNITED STATES PATENT OFFICE.

JOHN C. HART, OF NILWOOD, ILLINOIS.

GATE.

1,413,403.

Specification of Letters Patent. Patented Apr. 18, 1922.

Application filed January 24, 1921. Serial No. 439,492.

To all whom it may concern:

Be it known that I, JOHN C. HART, a citizen of the United States, residing at Nilwood, in the county of Macoupin and 5 State of Illinois, have invented certain new and useful Improvements in Gates, of which the following is a specification, reference being had therein to the accompanying drawings.

10 This invention relates to gates and has for an object to provide a gate with a swinging and a relatively sliding panel with improved means whereby the gate may swing to open position with the sliding panel in 15 any of its various slideable positions.

A further object of the invention is to provide a gate having a sliding panel which opens relative to a hinged, or swinging, panel, producing by the actuation of the 20 sliding panel, a smaller aperture for foot passengers, or the like, and permitting the swinging of the entire structure for the passage of vehicles, and the like.

A further object of the invention is to 25 provide improved elements and units of each of the two panels which will co-act to produce the completed structure.

With these and other objects in view the device comprises certain novel elements, 30 units, parts, combinations and functions as will be hereinafter more fully described and claimed.

In the drawings:

Figure 1 is a view of the improved gate 35 in side elevation shown in closed position;

Figure 2 is a view of the improved gate in side elevation with the sliding panel moved to open position;

Figure 3 is a top plan view of the gate 40 with the sliding panel in open position, as shown at Figure 2;

Figure 4 is a top plan view of the improved gate opened upon the swinging panel with the sliding panel at full extended position;

Figure 5 is a detail fragmentary perspective view showing the construction of the several parts, and

Figure 6 is a detail transverse sectional view, as indicated by line 6—6 of Figure 5.

Like characters of reference indicate corresponding parts throughout the several views.

The improved gate which forms the subject matter of this application comprises a panel shown as an entirety at 10 hinged to

a supporting post 11 in any approved manner, as by the ears 12 carried by the panel engaging upon pintles 13 carried rigidly by the post. The panel 10 may be of any 60 desired construction, but must comprise a top bar and end rail 14 and some means for holding the two in proper relation, as the inclined brace 15. The exact construction of the swinging panel is immaterial to the 65 present invention, dependent only upon structural means for pivotally supporting the top bar which carries rollers 16 attached thereto in any approved manner, as by keepers 17 which may be applied in any 70 manner, directly to the top bar 10 or to the end rail 14, or otherwise, the necessity being that it be supported at the top rail. Through the keepers 17 and bearing upon the rollers 16, a rail 18 of the sliding panel operates 75 preferably, though not necessarily, provided with a metal shoe 19, which makes immediate contact with the rollers 16. The rail 18, forming as it does the top rail of the sliding panel, is completed in its structure 80 by means of end bars 20 and such intermediate rails 21 as may be found desirable to complete the panel structure, the invention being in no way limited to the number of these rails or the use of cross bars 22 or 85 other strengthening means. The end rail 14 of the swinging panel is also provided with a keeper 23 secured to the rail in any approved manner, as by the rivet 24 which resists the tendency of the sliding panel to 90 swing upon the rail 18 as a pivot. The sliding panel also carries a catch member 25 positioned to be engaged by a bail 26 carried by the post 27, which is spaced from the post 12 such a distance as to permit the entire gate structure in its elongated position 95 to swing between such posts and the latch member 25 to engage and latch with the bail 26.

In operation, the gate as shown at Figure 100 1 is in closed position and the panels latched by the engagement of the bail 26 with the latch member 25. For the passage of foot passengers, or the like, the sliding panel is disengaged by raising the bail 26 and the 105 panel slidably moved longitudinally relative to the swinging panel. This opens an aperture as disclosed at Figure 2 for the passage of foot passengers, or the like. When the gate is to be opened to permit the passage 110 of vehicles, or the like, it may be opened from the position as shown at Figure 1 by

swinging to the position shown at Figure 4, or it may be swung about the hinging of the swinging panel when the sliding panel is in the position shown at Figures 2 and 3. 5 This latter arrangement of parts is desirable at times of high wind, or the like, which makes the opening of the gate difficult or difficult to maintain the gate in open position when the opening has been securing 10 without fastening, furnishing, as it does, a balanced construction, so that the wind pressure is substantially equalized upon opposite sides of the hinging.

What I claim to be new is:

15 A combination swinging and sliding gate comprising a plurality of horizontal bars connected by end supports, a pivoted carriage, one of the bars slidable upon the car-

riage, an intermediate vertical upright, the upright clearing the slidable bar, and a 20 limiting member upon the opposite side of the gate from the upright, the limiting member mounted to the carriage and adapted to limit the sliding movement of the gate by striking an end brace when the gate is fully 25 opened by sliding and adapted to be in vertical alinement with the upright when the gate is closed and depending sufficient to co-operate with the upright for bracing the structure intermediate its ends. 30

In testimony whereof I hereunto affix my signature in presence of two witnesses.

JOHN C. HART.
